UNITED STATES PATENT OFFICE.

WILLIAM T. CLARK, OF PHILADELPHIA, PENNSYLVANIA, ASSIGNOR TO OTIS
ELEVATOR COMPANY, OF JERSEY CITY, NEW JERSEY, A CORPORATION OF
NEW JERSEY.

SHOCK-ABSORBER.

1,140,357.

Specification of Letters Patent. Patented May 25, 1915.

Application filed November 28, 1913. Serial No. 803,385.

To all whom it may concern:

Be it known that I, WILLIAM T. CLARK, a citizen of the United States, residing in Philadelphia, in the county of Philadelphia 5 and State of Pennsylvania, have invented a new and useful Improvement in Shock-Absorbers, of which the following is a specification.

My invention relates to a shock absorber 10 for gearing, and one of its objects is to provide a device especially applicable to that type of gears known as "tandem gears" in common use with electric elevators, which device is simple in construction and has the 15 effect of taking up any jar or shock which may be present in such gears. This and other objects of the invention will appear in the following specification in which I will describe an embodiment and at the end of 20 which I will set forth its novel features in claims.

Referring to the drawings; Figure 1 is a diagrammatic view of certain parts of a common form of elevator employing tandem 25 gearing, and shows my invention applied thereto; Fig. 2 is a sectional side elevation of a device embodying my invention; Figs. 3, 4 and 5, are diagrammatic views of certain parts of the gearing to which my invention 30 is applied, and these figures are shown for the purpose of illustrating the operation of the device; Fig. 6 is a wiring diagram of electrical circuits of a typical electric elevator containing an embodiment of my invention. 35

Referring to Fig. 1, I show a reversible electric motor 10 which is connected to rotate a shaft 11 in both directions. Two oppositely pitched worms 12 and 13 are upon 40 this shaft and these worms mesh respectively with worm gears 14 and 15 which are also in mesh with each other or are otherwise connected to run together. On the shaft of gear 15 is mounted a rope or cable drum 16. From one side of this drum a cable 17 runs up over a sheave 18 at the top of the elevator hatchway, and is fastened to the car 19.

20 is a "back-drum" counterweight, that 50 is it is connected with the back of the hoisting drum 16 by a rope or cable 21 which runs over a supporting sheave 22 and a guiding sheave 23 to the drum. If, as is sometimes the case, the hoisting mechanism is located

at the top of the shaft, the sheaves 18, 22, 55 55 and 23 may be omitted.

The foregoing parts have been described but briefly for they do not of themselves form any part of the present invention.

As is well known, gearing of this and 60 similar character requires no end thrust bearings for the intermeshing gears balance each other so far as end thrust is concerned. But it has been found that if there is any play or backlash between the teeth of the 65 gears, and worms, there is not only a disagreeable jar felt in the car, especially upon reversing, but that the severe strains put upon the gears under present elevator practice due to sudden starting and stopping of 70 the car increase this defect rapidly. I have found that the blow between the teeth may be cushioned and the resulting shock absorbed or eliminated by the use of some such simple device as that which I am about to 75 describe herewith. As will appear more fully, an unusual smoothness of operation is attained, and the wear on the gearing itself is greatly reduced as well as cable strains in starting and stopping cushioned. 80

Briefly, my novel shock absorber comprises an electrically controlled pressure device with means for applying a resilient pressure or stress upon one end or the other of the worm shaft 11 tending to move it 85 longitudinally, and is an improvement upon the spring actuated shock absorber disclosed in United States Patent, No. 1,037,205, issued to me on September 3, 1912, for shock absorber for gearings. 90

Referring to Fig. 2, I will describe the construction of a simple form of my device. The reference numeral 24 designates the gear casing of the hoisting mechanism at the end of the shaft 11 in which casing the shaft 95 is supported. This device comprises a housing 30 of iron or other magnetic material which is adapted to be fastened by bolts 35, 35, onto the end of the casing 24 in place of the cap which is usually placed over the 100 end of the shaft hole. This housing 30 contains a magnet winding 32 which is wound upon a spool 33 forming a solenoid within which lies the worm shaft 11 itself or a piece of soft iron 31 secured to the end of the 105 worm shaft. A soft iron plug 36 is screwed into one end of the housing 30 and may be secured in adjusted position by means of

lock nuts 34. This plug 36 furnishes a ready means for adjusting the air gap between the plug and the member 31 on the worm shaft and in this manner regulating the strength 5 of the magnetic pull upon the shaft when the magnet is excited. While the plug 36 may be adjusted within wide limits, it is intended never to have the plug and the member 31 actually touch each other, but always 10 to leave an air gap between the two even when the magnet is fully excited.

It may be seen that this simple device may readily be placed upon elevator mechanisms already installed and in daily operation, and 15 it may be made to exert an end pressure upon the shaft 11 varying in amount in accordance with the strength of the magnet 32 and the adjustment of the screw plug 36.

I will describe the operation of my invention by making reference to the diagrams, 20 Figs. 3, 4 and 5. It will be understood that the counterweight 20 is heavier than the car 19, so that when there is but a light load in the car the pull on rope or cable 21 will be greater than the pull on the rope 17. When the car is fully loaded, this condition 25 will be reversed. Let us assume first that the load on the car, together with the weight of the car itself just balances the counterweight 30 20. The weights then will have no tendency to rotate the drum 16 and the gears 14 and 15. Let us further assume that there is some play or back lash between the worms 12, 13, and gears 14, 15, respectively. Without my 35 device applied the shaft 11 is free to "float", that is to move back and forth longitudinally. With the conditions assumed and illustrated diagrammatically in Fig. 3, the shaft may assume a position with the teeth of the 40 worms midway between the teeth of the gears. In starting to rotate the shaft 11 in either direction there will be a jar or shock when the teeth of the worms strike against the teeth of the gears; this difficulty will be 45 greatly aggravated if the car and counterweight loads do not balance and the shaft 11 is rotated in a direction opposite to that of greatest pressure on the gearing.

Referring now to Fig. 4, it will be assumed 50 for purposes of illustration, that there is 6000 lbs. more strain put upon gears 14 and 15 by the counterweight than by the car. The condition then will be that this 6000 lbs. will be taken up equally at the 55 points A and B. But according to my invention I add at the end of shaft 11 a resilient end pressure in the direction of the arrow C, say of 500 lbs. This will decrease the pressure at A to 2500 lbs., and increase 60 the pressure at B to 3500 lbs. Under these conditions it may be noted that the maximum work of driving the elevator comes upon worm 13 and gear 15. Now if the driving pressure is reversed, and the worm 65 revolved, the tendency is for the worm tooth

to advance and strike tooth E of gear 15. But with resilient pressure, applied at one end of shaft 11, the latter is caused to move longitudinally, maintaining the contact between the worm and gear at B. It is in this manner that the jar of starting the elevator with gears of this general type is cushioned and overcome.

Now considering Fig. 5 and assuming that the pull of the car on gear 15 is 6000 lbs., 75 greater than that of the counterweight. This pull will be divided between the points F and G. But with 500 lbs. resilient longitudinal pressure in the direction of the arrow C, the pressure will be unequally divided and there will be 3500 lbs. pressure at F and 2500 lbs. pressure at G. Running the elevator under these conditions will make worm 12 and gear 14 do the greater part of the work. When the driving pressure is 80 reversed and the work revolved, the resilient end pressure upon the shaft will shift the latter to prevent the back of the worm tooth of worm 12 striking against tooth H of gear 14.

In the usual constructions, the worms 12 and 13 are made of steel and the gears 14 and 15 of bronze. The latter are capable of long wear but are peculiarly susceptible to hammer blows such as they get as soon as there is a slight amount of backlash between them and the worms. With my invention applied, the shocks or blows are eliminated so that the gears wear much longer. It is only necessary that sufficient 90 pressure be applied to the shaft 11 in the direction of the arrow C to move the shaft longitudinally with an acceleration equal to the difference of accelerations of the gear teeth and of the worm teeth in the same direction, that is, the annular acceleration of the worm times the lead of the screw. The figures used in explaining the foregoing operations are arbitrarily selected for illustration only.

Not only does this invention decrease the wear of the gears, but it may now be seen that the operation on the car will be smoother when starting and stopping due to the fact that the worms and gears are held in contact, and that sudden strains throughout the ropes and other parts of the hoisting apparatus will be greatly relieved.

While it would be possible and practical to maintain the magnet 32 of the shock absorber energized at all times, there is no necessity of having it consume current except during the starting and stopping period. In order therefore, to save current and to employ a magnet of moderate size without danger of overheating, I have devised a system of electrical circuits shown in Fig. 6.

Referring to Fig. 6, I show a car switch 37 adapted to close a circuit to either of the reversing switches 38 and 39 which in turn

close a circuit to the motor 10 for either direction of rotation. An accelerating magnet 40 is connected by the reversing switches across the motor armature and operates automatically to short circuit the contacts 1, 2, 3, 4 and 5 in the order named, successively to cut out the starting resistance 44 in starting the motor. The contact 3 carries an insulated contact which is one of a pair 10 of contacts 6, which are normally in closed position when the motor is slowing down or at rest. A resistance 43 is arranged to be thrown across the motor armature when the reversing switches 38 and 39 are in lowermost position and its function is to provide a dynamic brake action on the motor tending to stop it. The usual electric brake apparatus I have not shown but it is to be understood that I contemplate using such brake apparatus 15 ranged and connected in the customary manner. A relay 44 controls a pair of contacts 45 and is connected across the motor armature. 46 designates a resistance which is normally in series with the magnet 32 and shunt field winding 42 of the motor.

The operation of the above described system of circuits is as follows: With the parts in the position shown and the motor at rest, a circuit is maintained from the + main 30 through the resistance 46 and through the magnet 32 and contacts 5 in series and also through the motor field 42. The ohmic resistance of the resistance 46 and the magnet 32 is of such value that but a very feeble current flows in the magnet 32 and its pull on the shaft 11 is practically negligible. As soon as either of the reversing switches 38, 39, is raised to start the motor, the resistance 46 is short circuited and the magnet 32 and motor field receive full current from the mains and the motor starts with the pull on the shaft 11 at a maximum. As soon as the motor has accelerated to substantially one half full speed the contacts 3 are 40 automatically closed by the accelerating magnet 40 and the contacts 6 simultaneously opened, thereby interrupting the circuit to the magnet 32. In stopping the elevator, the reversing switch is dropped, 45 thereby closing a short circuit around the motor armature including the resistance 43, and at the same time interrupting the circuit to the accelerating magnet 40 at one of the contacts 47. The contact 6 immediately close, again establishing the circuit to the magnet 32 and also an additional circuit to this magnet from the + main by way of the contacts 45 of the relay 44, which latter being connected across the motor armature 50 is now in raised position. The resistance 46 is short circuited and the magnet 32 and motor field receive full line current, as long as the relay remains in raised position. The relay 44 is so connected and arranged that 55 it will remain in raised position until the

motor counter electro motive force practically disappears, or in other words until the motor substantially comes to rest, hence the dynamic brake action upon the motor takes place under maximum field strength and the pull exerted by the magnet 32 on the worm shaft is effective during the entire stopping period of the motor. When the motor finally comes to rest the relay 44 becomes dead and the contacts 45 are opened and the resistance 46 is once more included in the circuit of the relay 32 and motor field.

In reviewing this operation it will be seen that the magnet 32 of the shock absorber is very slightly energized when the motor is at rest and is fully energized during the acceleration and deceleration of the motor. The slight energization of the magnet 32 insures that it will immediately come up to full strength upon closing the motor circuit so that the maximum pull of the shock absorber is available the instant the motor circuit is closed and the worm shaft 11 exerts a driving torque. Since the magnet 32 only takes an appreciable current during the starting and stopping period the current consumed by the shock absorber is reduced to a minimum and is only used when most needed. For this reason the magnet 32 may be very moderate in size and still be free 95 from danger of overheating, whereas if the magnet took full current at all times it would have to be much larger and more expensive to construct.

While the system of electrical circuits 100 shown in Fig. 6 will accomplish the desired end, said system is only illustrative of one method of control, and it is observed that other arrangements of circuits could easily be devised so as to produce the proper 105 action of the shock absorber. Moreover the arrangement and construction of the shock absorber itself is illustrated in its simplest form but I do not limit myself to this specific arrangement of parts or to the specific 110 arrangement of electrical circuits.

If desired the magnet 32 could easily be arranged to exert a thrust or end pressure upon the shaft 11 in the opposite direction to that shown, or the magnet could be located at an intermediate position on the shaft or at the other end of the shaft if so desired, the ultimate result being the same in each case.

What I claim is:—

120

1. In an elevator, tandem gearing comprising a shaft having oppositely pitched worms thereon, and magnetic means for applying a longitudinal stress in said shaft.

2. In an elevator, a shaft having right and left hand worms, gears meshing with said worms and connected with each other, and electrical means for applying a longitudinal stress in said shaft.

3. In an elevator, a shaft having right and 130

- left hand worms, gears meshing with said worms and connected with each other, and electrical means tending to effect a longitudinal movement of said shaft.
5. In an elevator, a shaft having right and left hand worms, gears meshing with said worms and with each other, and magnetic means for exerting a longitudinal pull on said shaft.
10. 5. In an elevator, a shaft having right and left hand worms, gears meshing with said worms and with each other, and magnetic means for exerting a longitudinal pull on one end of said shaft.
15. 6. In an elevator, a shaft having right and left hand worms, gears meshing with said worms, and connected with each other, and an electromagnetic shock absorber arranged to effect a longitudinal movement of the said shaft.
20. 7. In an elevator, a shaft having right and left hand worms, gears meshing with said worms and connected with each other, an electromagnetic shock absorber adapted to effect a longitudinal stress in said shaft, and means for adjusting the amount of said stress.
25. 8. In an elevator, tandem gearing comprising a shaft having oppositely pitched worms thereon, gears meshing with said worms, and arranged to drive each other, and electromagnetic means for compensating for the backlash in said gearing.
30. 9. In an elevator, tandem gearing comprising a shaft having oppositely pitched worms thereon, gears meshing with said worms and arranged to drive each other, a device for effecting a longitudinal movement of said shaft, and means for effecting the operation of said device only while said shaft is undergoing a change in relative speed.
35. 10. In an elevator, tandem gearing com-
- prising a shaft having oppositely pitched worms thereon, gears meshing with said worms and arranged to drive each other, an electromagnetic device for moving said shaft longitudinally, means for rotating said shaft, and means controlled by said shaft rotating means for effecting the operation of said device.
40. 11. In an elevator, tandem gearing comprising a shaft having oppositely pitched worms thereon, gears meshing with said worms and arranged to drive each other, a motor arranged to rotate said shaft, and means controlled by said motor for effecting a longitudinal stress in said shaft.
45. 12. In an elevator, tandem gearing comprising a shaft having oppositely pitched worms thereon, gears meshing with said worms and arranged to drive each other, a motor arranged to rotate said shaft, an electromagnetic device arranged to effect a longitudinal pull upon said shaft, and a circuit for said device controlled by the motor in starting and stopping.
50. 13. In an elevator, tandem gearing comprising a shaft having oppositely pitched worms thereon, gears meshing with said worms and arranged to drive each other, a motor arranged to rotate said shaft, an electromagnetic device arranged to effect a longitudinal pull upon said shaft, and means for fully energizing said electromagnetic device when the motor is accelerating and decelerating and for partially energizing the said device while the motor is at rest.
55. In testimony whereof, I have signed my name to this specification in the presence of two subscribing witnesses.
60. WILLIAM T. CLARK.
